UNITED STATES PATENT OFFICE.

ABRAHAM CALVERT SCARR, OF HARRISTON, CANADA.

WHIFFLETREE.

SPECIFICATION forming part of Letters Patent No. 681,583, dated August 27, 1901.

Application filed June 22, 1901. Serial No. 65,615. (No model.)

To all whom it may concern:

Be it known that I, ABRAHAM CALVERT SCAARR, a subject of the King of Great Britain, and a resident of Harriston, in the Province 5 of Ontario and Dominion of Canada, have invented a new and Improved Whiffletree, of which the following is a full, clear, and exact description.

The object of this invention is to provide a 10 whiffletree of simple novel construction which is inexpensive to construct, is very durable and strong, and that may be varied in dimensions to suit the service it is to perform.

The invention consists in the novel construction and combination of parts, as will be hereinafter described, and defined in the appended claims.

Reference is to be had to the accompanying drawings, forming a part of this specification, 20 in which similar characters of reference indicate corresponding parts in both figures.

Figure 1 is a plan view of the improved whiffletree; and Fig. 2 is a transverse sectional view, substantially on the line 2-2 in 25 Fig. 1.

The improved whiffletree is mainly constructed of metal bars that are so combined and arranged as to afford a very light, strong, and durable pull-bar or whiffletree for a 30 vehicle designed to be drawn by horses or other draft-animals, as will now be specifically described.

10 and 11 respectively represent a rear bar and a front bar of the whiffletree, and said bars 35 as shown are duplicates of each other, separately consisting of a straight piece having suitable length, the sides thereof being parallel with each other, as are also the edges.

A truss-bar 12 is a coacting member with 40 the flat bars 10 11 and is located between said bars, as shown in Fig. 1. At an equal distance from each end of the truss-bar 12 two obtuse-angular bends *a a* are formed thereon, affording a flat intervening portion 45 at and near the longitudinal center of the same, as shown at *b* in Fig. 1, which portion is seated upon the inner side of the front bar 11 of the whiffletree. A spacing-block 13 is introduced between the flat portion *b* of the 50 truss-bar 12 and rear parallel bar 10, consisting of an oblong rectangular billet, preferably of hard wood. A loop-plate 14 is provided as

a coupling member for the whiffletree, consisting of a metal strip having substantially a V shape, providing an eye *c* at its longitudinal center and two flat limbs extended oppositely from said eye, as shown in Fig. 1. The loop-plate 14 is imposed upon the front bar 11 opposite the spacing-block 13 and is secured in place by two rivet-bolts *d*, that are inserted 55 through alined perforations in the loop-plate limbs, bars 10, 11, and 12, and the spacing-block 13, which disposes the eye *c* at the longitudinal center of the whiffletree, projecting from the front side thereof. Near each extremity of the truss-bar 12 an obtuse-angular bend *e* is formed reversely of the bends *a* and of such degree as to provide two end portions *h* thereon, which are imposed upon corresponding end portions of the rear bar 10 60 and have level contact with the inner surface thereof. Between the portions *h* of the truss-bar 12 and the forward surface of the front bar 11, at and near each end of the same, two like spacing-blocks 15 are inserted. Two similar loop-plates 16 are completing members of the improved whiffletree, and each comprises a 65 flat metal bar bent to produce a loop *g* thereon at its center of length. The loop-plates 16 are held upon the rear surface of the bar 10 70 respectively at and near its ends by two rivet-bolts *i* for each of said loop-plates, these pairs of rivet-bolts passing through spaced perforations that extend through the limbs of the loop-plates, the rear bar 10, portions *h* of the truss-bar 12, spacing-blocks 13, and front bar 11, 75 the ends of the bolts being riveted or otherwise secured from longitudinal displacement.

It will be seen that the peculiar construction of the improved whiffletree affords great 80 strength and adapts it to withstand very heavy draft strains applied upon the two loop-plates 16 and the central loop-plate 14. Furthermore, the body of the whiffletree is 85 very light and may be manufactured without using forge heat, which evidently cheapens its production.

In constructing the truss-bar 12 I preferably turn up the edges at a right angle, which renders said bar very stiff and strong.

Having described my invention, I claim as new and desire to secure by Letters Patent—

1. A whiffletree, comprising two straight and parallel metal bars, an intervening bent

truss-bar, two spacing-blocks at respective ends of said bars, a central spacing-block between the truss-bar and one straight bar, and means to secure the bars and spacing-blocks together.

2. A whiffletree, comprising two straight and parallel bars, a truss-bar bent at two points near the center, and also reversely at two points near the ends thereof, a spacing-block near each end of the bent truss-bar intervening it and the front straight bar, a spacing-block between the middle portion of the truss-bar and the rear straight bar, and means to secure the bars and spacing-blocks together.

3. A whiffletree comprising two straight

and parallel bars, that are front and rear members of the whiffletree, a truss-bar bent at two points near the center, and also reversely at two points near the ends thereof, 20 a spacing-block near each end of the truss-bar intervening it and the front straight bar, a spacing-block between the middle portion of the truss-bar, a loop-plate near each end of the rear bar, a loop-plate near the center 25 of the rear bar, and means to secure the loop-plates, bars and spacing-blocks together.

ABRAHAM CALVERT SCARR.
